US00D730907S

(12) **United States Design Patent**
Lim et al.

(10) **Patent No.:** US D730,907 S
(45) **Date of Patent:** ** Jun. 2, 2015

(54) **MEMORY CARD**

(71) Applicant: **SAMSUNG ELECTRONICS CO., LTD.**, Suwon-si (KR)

(72) Inventors: **Gwang-Man Lim**, Seoul (KR); **Il-Mok Kang**, Suwon-si (KR); **Seok-Jae Han**, Seoul (KR); **Sang-Chul Kang**, Hwaseong-si (KR); **Seok-Cheon Kwon**, Yongin-si (KR); **Seok-Chan Lee**, Hwaseong-si (KR)

(73) Assignee: **SAMSUNG ELECTRONICS CO., LTD.**, Suwon-si (KR)

(**) Term: **14 Years**

(21) Appl. No.: **29/507,079**

(22) Filed: **Oct. 23, 2014**

(30) **Foreign Application Priority Data**

May 2, 2014 (KR) 30-2014-0022384
